T. A. HENDERSON.
EVAPORATIVE COOLER.
APPLICATION FILED MAY 2, 1913.

Patented Mar. 10, 1914.

UNITED STATES PATENT OFFICE.

THOMAS A. HENDERSON, OF MART, TEXAS.

EVAPORATIVE COOLER.

1,089,837.

Specification of Letters Patent. Patented Mar. 10, 1914.

Application filed May 2, 1913. Serial No. 765,159.

To all whom it may concern:

Be it known that I, THOMAS A. HENDERSON, a citizen of the United States, residing at Mart, in the county of McLennan and 5 State of Texas, have invented a new and useful Evaporative Cooler, of which the following is a specification.

This invention relates to an evaporative cooler or refrigerator.

10 An object of the present invention is to provide an evaporator cooler or refrigerator adapted to be cooled by the evaporation of water.

A further object is to provide a receptacle 15 with a plurality of shelves therein upon which may be positioned various articles which are to be maintained in a cool condition and to furthermore provide ventilating tubes leading to each compartment defined 20 by the shelves so that the air will be maintained in a fresh condition.

A further object is to provide a refrigerator with a water containing pan at the top thereof and into which extends a cloth, the 25 same encompassing the entire refrigerator and terminating in a receiving pan positioned therebeneath, the water being adapted to soak its way through the cloth, flowing downwardly therethrough and being evaporated therefrom to thereby effectually cool 30 the articles disposed within the refrigerator.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made with 35 40 in the scope of what is claimed, without departing from the spirit of the invention.

In the drawings accompanying this specification and forming a part thereof, the preferable form of my invention is illustrated, in 45 which:—

Figure 1 is a view in perspective of my improved milk cooler with portions of the jacket broken away. Fig. 2 is a front view in elevation thereof without the jacket. Fig. 50 3 is a vertical cross sectional view illustrating the construction of the cooler and showing the ventilating tubes.

Referring to the drawings in which similar reference numerals designate corresponding parts throughout the several views, 1 55 represents the lower receiving pan through

which extend the upright supporting posts 2, the same being illustrated as being formed of angle iron and to the upper extremities of which is secured the angle member 3 30 which is adapted to removably support a liquid containing pan 4.

Rigidly secured to the posts 2 at various intervals therealong are the angle brackets 5 similar to the angle bracket 3 hereinbefore 35 referred to. The angle brackets 5 are adapted to support the shelves 6, there being three of the shelves illustrated in the present drawings. The exact number of shelves however, is optional and depends largely 40 upon the size of the cooler. The angle brackets 5 extend between the four upright posts 2 which define the corners of the cooler.

Hingedly secured to the front of the cooler 45 are the swinging doors 7 provided with a suitable latch 8 whereby they will be retained in a closed position. The doors, as are the other portions of the cooler, are formed in the nature of skeleton work 50 extending between which are the screens 9. Rigidly secured to the upright posts and extending along the two sides and back of the cooler is the screen 10, the same being foraminous or reticulated so that the articles disposed upon the shelves 6 will be cooled by 55 the flow of cool air through the said screens.

In order that the compartments defined by the shelves may be properly ventilated and what may be termed isolated from the remaining shelves, the ventilating pipes 11 are rigidly secured to the sides of the cooler and are provided with a plurality of flues 12 extending therethrough and which flues communicate with the said compartments. By so 60 isolating the various portions of the cooler it prevents articles in one compartment acquiring the taste of articles in the other compartments and at the same time the various flues provide that the air within each compartment will be maintained in a fresh condition.

As illustrated in Fig. 1 of the drawings, a fabric or cloth-like jacket 13 which is formed of some absorbent textile material 65 is provided, the upper extremity of which overlaps the liquid containing pan 4 and extends therein. The bottom of the jacket extends down into the receiving pan 1 and as the liquid is absorbed by the jacket the 70 same passes down through the jacket, with the result that the entire jacket will be 75 80 85 90 95 100 105 110

maintained in a moist condition, the water or liquid being constantly evaporated therefrom to thereby absorb the heat from the surrounding medium to thereby cool the various articles disposed within the cooler. The jacket 13 is provided with two apertures 14 adjacent the top, which apertures allow the ventilating pipes 11 to pass therethrough. The jacket is illustrated in the drawings 10 as being provided with a number of buttons and button-holes 15, it being understood however, that any desirable means may be employed whereby the meeting edges of the jacket may be suitably held together and at 15 the same time be easily detachable, to thereby render accessible the interior of the cooler. In order that the jacket 13 will suitably isolate the various compartments the outstanding flange members 16 are rigidly secured to the sides of the cooler and terminate flush with the ventilating pipes 11, the result being that although the ventilating pipes 11 hold the jacket away from the sides of the cooler, the outstanding 25 flanges 16 will contact with the jacket and prevent the air from one compartment from circulating throughout the other compartments.

From the foregoing it will be apparent 30 that the improved cooler will by the evaporation of water, maintain the articles disposed therein in a cooled condition and that by the construction such as I have outlined,

the articles disposed on one shelf will be maintained in contact with fresh air and 35 suitably isolated from articles disposed on the other shelves.

Having thus described the invention what I claim is:—

An evaporative cooler comprising an upright frame, screens extending therebetween and forming the walls thereof, shelving extending transversely of said frame and defining compartments, independent flues extending along the side walls of said compartments and communicating therewith, outwardly extending ledges in alinement with the shelving and extending flush with the outer surface of said flues, and a textile jacket positioned around and lying in contact with the said screen-like walls and lying in contact with the flues and outstanding ledges, the side jacket and independent flues maintaining the various compartments in a non-communicating condition and preventing the passage of air between the various compartments, and means for maintaining the said jacket in a moist condition. 40 45 50 55

In testimony that I claim the foregoing as my own, I have hereto affixed my signature 60 in the presence of two witnesses.

THOMAS A. HENDERSON.
